(57) **CLAIM**

The ornamental design for a sensor enhanced meter, as shown and described.

DESCRIPTION

FIG. 1 is a top, back, right perspective view of a sensor enhanced meter, showing our new design;

FIG. 2 is a front elevational view thereof;

FIG. 3 is a back elevational view thereof;

FIG. 4 is a right side elevational view thereof;

FIG. 5 is a left side elevational view thereof; and,

FIG. 6 is a top plan view thereof.

The broken lines shown are included for the purpose of illustrating portions of the sensor enhanced meter that form no part of the claim.
